UNITED STATES PATENT OFFICE.

SAMUEL OWEN EDMONDS, OF NEW YORK, N. Y., ASSIGNOR TO HENDRICK MANUFACTURING COMPANY, OF CARBONDALE, PENNSYLVANIA, A CORPORATION OF PENNSYLVANIA.

SCREEN.

1,212,151.

Specification of Letters Patent.

Patented Jan. 9, 1917.

Application filed August 7, 1915. Serial No. 44,151.

To all whom it may concern:

Be it known that I, SAMUEL O. EDMONDS, a citizen of the United States, residing in the borough of Manhattan, city, county, and State of New York, have invented certain new and useful Improvements in Screens, of which the following is a specification.

The invention relates particularly to screens adapted for the separation of particles of coal into various sizes or for the elimination therefrom of impurities, such as dirt, slate, etc.

The invention is capable of use either while stationary but inclined, the material being fed continuously over the same, or mounted in a suitable frame, to which oscillating motion is imparted in manner well known in colliery practice in the anthracite and other coal regions.

In screens of the general type which this invention concerns, it is desirable that the separation of the particles occur as early in the passage of the material over the screening surface as possible, both because this results in most efficient utilization of the screening surface and also because the area of screening surface is thereby minimized. As against such early separation of the particles, is the fact that a very large percentage of slate particles and a substantial percentage of coal particles are of such fracture as to present to the screening surface a flat side or sides of too great magnitude to pass through the screen, as a result of which they frequently travel a considerable distance over the screening surface without passing therethrough. Such particles, if so treated as to present to the screening surface not the flat sides but the edge thereof, would readily pass through a screen perforation, thereby not only affecting its own early separation from the mass, but also making way for another particle or other particles to come into intimate contact with the screening surface.

The object of the present invention is to improve upon screens heretofore employed, chiefly in the respects above pointed out, whereby a device is provided of higher efficiency in the separating operation and the screening area, for a given quantity of material, minimized.

In carrying out my invention, I provide a preferably integral sheet of sheet-metal of stepped formation, each step, as well as the shoulder between the same and the next adjacent step being provided with a lateral series of longitudinally-extending slots, either of the same width or of gradually increasing width in the direction of flow of the material. The slots of one step are arranged in staggered relation to the slots of the adjacent step or steps, so that, for example, the webs between the slots of the first and third steps shall be opposite the slots of the second and fourth steps. These webs may, if desired, remain in the original level of the plate or may be canted slightly, either all in the same direction or each two adjacent webs in opposite directions, so as to present slightly inclined surfaces on either side of alternate slots in each series. Preferably, at a point approximately midway the slotted area, and extending, generally speaking, at right angles to the longitude of the slots, I provide the webs (or certain of them) bounding the slots with elevations or protuberances designed to contact with the material passing over the screening surface, to prevent the same from sliding with a side or face of the particles in contact with the screen but of such magnitude as not to pass through the openings thereof. These elevations or protuberances may conveniently be formed coincidently with the bending of the plate, to give it the stepped formation above referred to. Material falling upon the screen surface is, in my invention, practically continuously agitated, turned and its coaction with the slots of the screening surface facilitated, both by means of the elevations or protuberances and also by means of the shoulders bounding the several steps in the plate. As a result, the separation of particles of a size suitable to permit them to pass through the slots in the screening surface is facilitated and the ready and more accurate separation of the particles of the mass assured.

The invention is illustrated in the accompanying drawings, in which—

Figure 1 is a plan view of a screen provided with my invention, Fig. 2 is a longitudinal section on the line 2—2 of Fig. 1, and Figs. 3, 4 and 5 are enlarged frag-

mentary views, illustrating different forms which may be given the elevations or protuberances above referred to.

The screen is preferably formed of an integral sheet of steel, 1, in which, by means of a suitable punch-press, transverse series of slots, 2, are formed, leaving on all sides margins 3, which are imperforate save for such bolt-holes (not shown) as may be required to secure the plate to a suitable frame. In the drawings, the slots 2 are shown as of tapering form, *i. e.*, smaller at the ends nearest to the highest portion of the plate; they may however, if desired, be of the same width throughout.

After the sheet has been slotted as above described, it is formed, preferably by means of a suitable press, into a series of steps (see Fig. 2), each step being characterized by a shoulder 4, and each successive step, toward the right, being depressed below the level of the next adjacent step toward the left. As clearly shown in the drawings, the shoulders 4 are formed in the slotted portions of the plate, the slots of each series preferably extending beyond the shoulder 4 of that series and a short distance into the next adjacent step toward the right, the object being that particles of material turned or agitated at the point of location of the step shall have an opportunity to pass through the slots immediately below the highest portion of the shoulder, but if not, then that such particles, falling slightly beyond the ends of the slots on one step, shall fall upon the solid portion of the next adjacent step, such portion supplying adequate strength at a point where the screen is subjected to more than usual wear.

Either coincidently with giving the sheet the stepped formation or as a subsequent operation, the webs bounding the slots 2 may be slightly canted, in manner above described. Also, either coincidently with one or both such operations or by a subsequent operation, the web-bars bounding the slots of each step, (or certain of such web-bars or those of certain steps) are provided with integral elevations or protuberances 5, projecting upwardly (see particularly Fig. 2) from the otherwise substantially level surface of the step. These elevations or protuberances 5 may characterize only the webs between the slots or may extend entirely across the plate, therefore characterizing also the imperforate margins 3. To serve the purpose for which they are intended, however, it is necessary only that they be formed in the webs, so that the mass of material fed upon the screening surface may, early in its passage over such surface, come into contact with such elevations or protuberances, these having the effect to agitate and turn the particles of coal or other material to break up aggregations of such par-

ticles, and, in general, as above explained, to facilitate the passage of the particles through the slots of the screening surface and as early as possible in the passage of the material over such surface.

While for economy and ease of operation I prefer to form the elevations or protuberances in the manner above described and as illustrated in Figs. 1 and 2, it is not essential that the same take the particular form so illustrated and described, as I may, if desired, form the elevations or protuberances diagonally of the webs, as shown at 5', all the elevations running in the same direction or alternately in different directions, as shown at 5², Fig. 4. Or the elevations or protuberances may be arranged in two lines, each at an angle to the other, as illustrated in Fig. 5, and these lines may extend over the whole of the plate, as illustrated in full lines in said figure, or may be combined with marginal ridges 5³, having the effect to prevent too great accumulation of particles along the imperforate margins of the plate where the same may not be covered by the frame (not shown) to which the plate may be attached.

Under certain conditions, dependent, among other things, upon the character of the material being treated, and the incline (if any) of the screen, the extensions or protuberances may be omitted from certain of the webs or even from certain of the steps. To such extent as may be necessary to accomplish the purpose stated they should be provided, however, in one or another of the several forms herein indicated.

By means of the invention above described, a highly efficient screening device is provided, adapted for a variety of uses, as, for instance, in connection with loading chutes, or under revolving screens, or for the separation of slate from coal, and as aforesaid the screen may be used either stationary, the mass being fed continuously over its surface, or may be mounted to oscillate in a substantially horizontal (or slightly inclined) plane, to facilitate both the passage of the material and the agitation thereof to break up aggregations of particles and to bring into contact with the slotted screening surface particles adapted for passage therethrough as early as possible in the movement of the mass from the forward end of the device.

Having now described my invention, what I claim as new therein and desire to secure by Letters Patent is as follows:—

1. An integral screen of sheet-metal, provided at intervals with transverse shoulders determining areas or steps lying in different planes, each such area or step being provided with a series of substantially parallel slots, the slots of all the series extending in the same direction, and integral elevations or

protuberances formed in the working surface of the screen, in the path of material treated thereon, substantially as set forth.

2. An integral screen of sheet-metal, provided at intervals with transverse shoulders determining areas or steps lying in different planes, each such area or step being provided with a series of substantially parallel slots, and integral elevations or protuberances formed in certain of the webs bounding said slots, at points intermediate of the ends of said slots, substantially as set forth.

3. An integral screen of sheet-metal, provided at intervals with transverse shoulders determining areas or steps lying in different planes, each such area or step being provided with a series of substantially parallel slots whose ends extend over a shoulder adjacent to said step or area the slots of all the series extending in the same direction and into the next adjacent step or area, and integral elevations or protuberances formed

in the working surface of the screen, in the path of material treated thereon, substantially as set forth.

25

4. An integral screen of sheet-metal, provided at intervals with transverse shoulders determining areas or steps lying in different planes, each such area or step being provided with a series of substantially parallel slots whose ends extend over a shoulder adjacent to said step or area and into the next adjacent step or area, and integral elevations or protuberances formed in certain of webs bounding said slots, at points intermediate of the ends of said slots, substantially as set forth.
